Primary Examiner — Sheryl Lane*Assistant Examiner* — Emily A Caven(74) *Attorney, Agent, or Firm* — Martin & Associates,
LLC; Derek P. Martin(57) **CLAIM**

The ornamental design for a bird feeder base, as shown and described.

DESCRIPTION

FIG. 1 is an upper perspective view of a bird feeder base showing the new design;

FIG. 2 is a lower perspective view of the bird feeder base;

FIG. 3 is a top view thereof;

FIG. 4 is a bottom view thereof; and,

FIG. 5 is a side view thereof, where the front view, opposite side view and back view are identical to the side view in FIG. 5.

The broken lines showing portions of the bird feeder base form no part of the claimed design.
